UNITED STATES PATENT OFFICE.

JAMES BARBOUR, OF KINGSLAND, ARKANSAS.

DESIGN FOR A BROADAX.

SPECIFICATION forming part of Design No. 26,335, dated November 24, 1896.

Application filed October 12, 1896. Serial No. 608,650. Term of patent 7 years.

To all whom it may concern.

Be it known that I, JAMES BARBOUR, a citizen of the United States, residing at Kingsland, in the county of Cleveland and State of Arkansas, have invented and produced a certain new and original Design for a Broadax; and I do declare the following to be a full, clear, and exact description of the invention, such as will enable others skilled in the art to which it appertains to make and use the same.

My invention relates to a new and original design for a broadax for timbermen.

It relates to the entire configuration of the ax.

My invention relates particularly to an ax, as illustrated in the accompanying drawings, in which—

Figure 1 is a perspective view of a broadax embodying my design, and Fig. 2 is a central transverse section of the same.

The same reference-numerals indicate the same features of the design in the different views.

The leading features of my design appear 25 in the following description.

1 represents the beveled cutlery edge of the blade 2, having an integral chip-ridge 3 on one side. The side 4 of the blade 2 opposite to the chip-ridge 3 is longitudinally concaved, 30 as shown in the drawings in Fig. 2.

Having thus described my design, what I claim as new, and desire to secure by Letters Patent of the United States, is—

The design for a broadax, substantially as 35 herein shown and described.

In testimony whereof I hereunto affix my signature in presence of two witnesses.

JAMES BARBOUR.
